UNITED STATES PATENT OFFICE.

EMMA F. COATES, OF CHATTANOOGA, TENNESSEE.

MANIFOLDING CHECK-HOLDER.

1,075,090.

Specification of Letters Patent.

Patented Oct. 7, 1913.

Application filed June 18, 1912. Serial No. 704,335.

To all whom it may concern:

Be it known that I, EMMA F. COATES, citizen of the United States, residing at Chattanooga, in the county of Hamilton and State of Tennessee, have invented certain new and useful Improvements in Manifolding Check-Holders; and I do hereby declare the following to be a full, clear, and exact description of the invention, such as will 5 enable others skilled in the art to which it appertains to make and use the same.

This invention relates to improvements in manifolding check holders, and has for an object to provide a convenient portable 15 holder which will admit of ready insertion of separate sales slips.

A further object of the invention is to provide means removably secured to the holder for duplicating orders.

With these and other objects in view the invention comprises certain novel constructions, arrangements, and combinations of parts as will be more fully described and 20 claimed.

In the drawing—Figure 1 represents a plan view of the holder provided with checks and duplicating carbon papers. Fig. 2 is a view of the blank with one of the binding members removed. Fig. 3 is a transverse, 25 vertical section taken on line 3—3 of Fig. 1, and Fig. 4 is a detail view showing the spreading member for holding the binder to the holder.

Like characters of reference designate corresponding parts throughout the several 30 views.

The aim of this invention is to provide a separate check holder having binding means for the said checks, means for binding 35 a duplicating paper to the body of the holder, and means for alining the checks and duplicating paper.

In the drawings where one embodiment of the invention is shown, 1 represents a rectangular back board made of any suitable 40 material such as copper, brass or nickel plated with iron. Carried by the shorter end of the back board 1 is the clip 2, while carried by the longer side of the body is a 45 second clip 3: Inasmuch as these clips are identical in construction only one will be described.

As shown in Figs. 2 and 3 there are formed integral with back board 1 projecting ears 4. 50 Adapted to slip over ears 4 are curved spring members 5 provided with longitudinal slots

6 and 7; the ears 4 are designed to pass through the slot 6. Struck out from the back board 1 are bosses 8 which engage the upturned end of the curved spring member 5 and positively prevent the removal of the same. Held by the spring member 5 is a binding plate 9 having a rib 10 formed thereon and extending throughout its length. Member 9 is also provided with an ear 11 deformed integral therewith, which ear is designed to pass through slot 7 of spring member 5 and lie just above the ear 4 formed on back board 1. The rib 10 is formed on binding plate 9 and engages the downturned end of the curved spring member 5 to positively prevent removal of the same, rib 10 acting in this respect in the same capacity as boss 8. In this construction, illustrated most clearly in Fig. 3, it will be seen that 55 the binding plate 9 is resiliently held against back board 1 and at the same time is prevented from lateral movement by means of spring 5.

The boss 8 and the rib 10, as will be apparent, operate to prevent the accidental slipping of the binding plate 9 from the back board 1. Near one of the longer edges of the back board 1 are lugs 12, struck up from the body of the holder and designed to form 60 stops for alining the checks.

The edge of the holder opposite that carrying the clip 3 has formed integral therewith two projections 13 and 14 which when rolled, as most clearly illustrated in Fig. 3, 65 will form a holder for a pencil or pen.

In using this device separate checks, both original and duplicates, as indicated at 15, are slipped under the binder plate 9 of clip 2. When these checks are in place a suitable 70 reproducing sheet such as the carbon sheet indicated at 16 is inserted under the binding plate 9 of the clip 3. It is to be understood of course that any number of sheets of carbon may be held by the clip 3 as may be 75 required. The carbon 16 is then slipped between the original and duplicate checks 15 and the order written as is common with the present form of duplicating check books.

While the specific embodiment is shown 80 here it is to be understood that various changes may be made without departing from the spirit of the invention. The pencil holder might be placed on any of the edges; the position of the carbons and checks might 85 be changed and the holder itself may be given any finish which will conform with

the furnishings of the table upon which it is designed to be used.

What is claimed is:

1. The combination with a back board substantially rectangular, of a clip located at one end of the back board and stops equally spaced from one side of the back, and a second clip carried by the back between the line of the stops and the edge of said side.
- 10 2. The combination with a back board substantially rectangular, having stops extending upwardly from the surface of the back and equally spaced from one side, of a clip located at one end of the back substantially midway between the stops and the other side of the back board, and a second
- 15

clip carried at the first mentioned side of the back disposed between the stops and the adjacent edge of the back.

3. The combination with a back board substantially rectangular, of a clip located at one end of the back board, a line of stops located along one side of the back board, and a second clip carried by the back board on said side and located outside the line of stops.

In testimony whereof I affix my signature in presence of two witnesses.

EMMA F. COATES.
